UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

AIR-LIFT PUMPING MECHANISM.

1,426,563.

Specification of Letters Patent. Patented Aug. 22, 1922.

Application filed July 23, 1920. Serial No. 298,466.

To all whom it may concern:

Be it known that I, HALBERT B. HALVORSEN, a citizen of the United States, residing at Chicago, in the county of Cook and State of Illinois, have invented certain new and useful Improvements in Air-Lift Pumping Mechanisms, of which the following is a full, clear, and exact specification.

My invention relates to air lift pumping mechanisms and more particularly to foot pieces for such mechanisms.

An object of my invention is to provide an improved air lift pumping mechanism. Another object of my invention is to provide an improved foot piece for air lift pumping mechanisms. A further object of my invention is to provide an improved foot piece for air lift pumping mechanisms in which by reason of the disposition of the air discharge ports, a thorough emulsification of the water and air may be secured. Other objects of my invention will appear during the course of the appended specification and claims.

In the accompanying drawings, I have shown for purposes of illustration, one form which my invention may assume in practice.

In these drawings,—

Fig. 1 is a developed section through my improved foot piece on line 1—1 of Fig. 2.

Fig. 2 is a transverse section on the line 2—2 of Fig. 1.

It has been found that in foot pieces of relatively large diameter, thickness of the stream of water prevents to a certain degree the air escaping through the perforations in a central mixing tube from making a complete and perfect mixture. In order to overcome this difficulty, an outer mixing tube may be employed as will hereinafter be described to augment the working of the central tube, thus forcing the air into the stream of water passed through the pump chamber from the center and from its periphery, and in this way securing a perfect emulsion of the water and air.

My improved foot piece, which constitutes an improvement over that disclosed in my copending application, Serial No. 298,466, filed May 20, 1919, comprises an outer casting member 1 which is provided with a connection as shown at 2 for the downwardly extending air supply pipe. This connection opens into a lateral chamber 3 which

communicates with an annular chamber 4 formed between the outer casing member 1 and an inner annular casing member 5. The air chamber 4 to which downwardly flowing air is admitted serves as a reservoir from which air is discharged by the passages 7, the latter being directed in a generally radial direction into a column of water rising through the foot piece. The foot piece is provided at its upper end with a venturi throat 8 and, at a point above this throat, is secured to a riser pipe 9. The member 5 is provided adjacent its upper end with a transverse portion 10 which is hollow, as indicated at 11, and which at a point adjacent its center is expanded as at 12 to provide a socket for the reception of a mixing tube 13. This mixing tube is of the general shape of two cones placed base to base and from its lower end expands in diameter for a short distance, as indicated at 14. From its point of maximum diameter it tapers gradually to its point of attachment 15 to the socket 12. The lower end of the mixing tube 13 is closed by means of a suitable plug as indicated at 16, this plug being preferably conical in form. By reason of the double conical shape of the mixing tube 13, the water passing through the riser pipe is smoothly separated into an annular ascending column and to permit its passage beyond the opposite end of the central mixing tube in as uninterrupted and undisturbed a manner as possible, a conical cap is located at the upper end of the mixing tube, this cap being designated as 17. The passages 11, it will be noted, serve to conduct the air brought into the member 3 to the interior of the central mixing tube 13 and this air is discharged by way of passages 18 in generally outward radial directions in such manner as to thoroughly aerate and emulsify the water passing between the concentrically arranged mixing tubes.

It will be noted that at the lower end of the chamber 4 I have provided a vent 19 which constitutes a sand outlet, the function of this vent being to permit the escape of sand which might get into the chamber 4 especially during the period immediately following the turning off of the air to the pump.

While I have in this application specifically described one form which my invention

may assume in practice, it will be understood that this form of the same is shown for purposes of illustration and that the invention may be modified and embodied in 5 other forms without departing from its spirit or the scope of the appended claims.

What I claim as new and desire to secure by Letters Patent is:

1. In an air lift pump, a foot piece comprising means for dividing the ascending column of liquid into an unbroken annulus, and means for simultaneously aerating said annulus from both sides thereof as it is formed and while it is still unbroken. 10
2. In an air lift pump, a foot piece comprising a casing member, an inwardly extending support member at the upper end thereof, and means depending therefrom for dividing the ascending column of liquid 15 into an unbroken annulus and aerating the same.
3. In an air lift pump, a foot piece comprising a casing member, a diametrically extending support member at the upper end 20 thereof, a mixing tube depending therefrom and dividing the ascending column of liquid into an unbroken annulus, and means for supplying aerating fluid to said mixing tube through said support member.
4. In an air lift pump, a foot piece comprising an external casing member and an internal casing member forming an annular chamber, a transversely extending connection between the opposite sides of said annular chamber adjacent the upper end thereof, a mixing tube depending from said transverse member, and means for supplying aerating fluid from said annular chamber and from said mixing tube to the ascending column of liquid. 30
5. In an air lift pump, a foot piece comprising concentrically disposed members forming an annular chamber between them and a cylindrical chamber within the inner one thereof, a support member extending transversely across said cylindrical chamber and arranged at the upper end thereof, an aerating tube coaxially disposed with respect to said cylindrical chamber and supported by said transverse member, and means for supplying aerating fluid to the column of liquid passing between said aerating tube and the inner one of said first mentioned members simultaneously from opposite sides. 45
6. In an air lift pump, a foot piece comprising concentrically disposed members forming an annular chamber between them and a cylindrical chamber within the inner one thereof, a support member extending transversely across the upper end of said cylindrical chamber, a mixing tube coaxially disposed with respect to said cylindrical chamber and supported by said support member, and means for supplying 50
- 65

aerating fluid to the column of fluid passing between said mixing tube and the inner one of said first mentioned member simultaneously from opposite sides, said mixing tube having a conical point at its lower extremity. 70

7. In an air lift pump, a foot piece comprising concentrically disposed members forming an annular chamber between them and a cylindrical chamber within the inner one thereof, a support member extending transversely across the upper end of said cylindrical chamber, a mixing tube coaxially disposed with respect to said cylindrical chamber and supported by said support member, and means for supplying aerating fluid to the column of fluid passing between said mixing tube and the inner one of said first mentioned members simultaneously from opposite sides, said mixing tube having a conical point at its lower extremity, and tapering from a point a short distance above its lower extremity toward its upper end. 80

8. In an air lift pump, a foot piece comprising concentrically disposed members forming an annular chamber between them and a cylindrical chamber within the inner one thereof, a transverse support member extending transversely of said cylindrical chamber and arranged at the upper end thereof, a mixing tube coaxially disposed with respect to said cylindrical chamber and supported by said transverse member, and means for supplying aerating fluid to the column of fluid passing between said mixing tube and the inner one of said first mentioned members simultaneously from opposite sides, said mixing tube having a conical point at its lower extremity, and tapering from a point a short distance above its lower extremity toward its upper end, and being provided beyond its upper extremity with a conical cap. 90

9. In an air lift pump, a foot piece comprising concentrically disposed members forming an annular chamber between them and a cylindrical chamber within the inner one thereof, a transverse support member extending transversely of said cylindrical chamber and arranged at the upper end thereof, a mixing tube coaxially disposed with respect to said cylindrical chamber and supported by said transverse member, and means for supplying aerating fluid to the column of fluid passing between said mixing tube and the inner one of said first mentioned members simultaneously from opposite sides, said mixing tube having a conical point at its lower extremity and tapering from a point a short distance above its lower extremity toward its upper end, and being provided at its upper extremity with a conical cap, and said external chamber member being provided with a venturi throat at a point above said mixing tube. 100

10. In an air lift pump, a foot piece comprising an annular air chamber, upwardly directed passages for discharging air therefrom to the liquid to be pumped, and means
5 arranged at the bottom of said air chamber and permitting the escape therefrom of such solid matter as may obtain entrance to said air chamber through said upwardly directed passages, said means during pumping op-
10 eration of said foot piece operating as an aerating means discharging to the up-
wardly moving column of liquid.
11. In an air lift pump, a foot piece com-
prising means for dividing the ascending column of liquid into an unbroken annulus, 15 means for supporting said annulus forming means disposed at the upper end thereof, and means for simultaneously aerating said annulus from both sides thereof ar-
ranged below said supporting means and 20 including jet forming means formed in said first mentioned means.

In testimony whereof I affix my signature.

HALBERT B. HALVORSEN.
